UNITED STATES PATENT OFFICE.

HENRY BOTTJER, OF NEW YORK, N. Y.

WINDOW-CLEANING PLATFORM.

1,088,525.

Specification of Letters Patent.

Patented Feb. 24, 1914.

Application filed July 8, 1913. Serial No. 777,219.

To all whom it may concern:

Be it known that I, HENRY BOTTJER, a citizen of the United States, and a resident of the city of New York, borough of Brooklyn, in the county of Kings and State of New York, have invented a new and Improved Window-Cleaning Platform, of which the following is a full, clear, and exact description.

10 This invention relates to temporary platforms or scaffolds and has particular reference to means for supporting an operator and cleansing materials in the cleaning of windows.

15 Among the particular objects of this invention is to provide a platform of the character indicated which may be adjusted to fit any ordinary size of window and which will be strong and reliable when used in any 20 position of adjustment with respect to the size of the window.

25 The invention contemplates, furthermore, a number of details of specific construction which render this device safe in use and 30 easily transportable from one window to another or for storing away.

30 The foregoing and other objects of the invention will hereinafter be more fully described and claimed and illustrated in the drawings forming a part of this specification in which like characters of reference indicate corresponding parts in all the views, and in which—

Figure 1 is a perspective view of a device 35 made in accordance with this invention as it would be seen from the inside of a building and looking down at an angle upon the seat portion of the platform, the window being indicated in dotted lines; Fig. 2 is an end 40 view of the device folded; Fig. 3 is a plan view of the same; Fig. 4 is a vertical section on the line 4—4 of Fig. 3; and Fig. 5 is a similar section on the line 5—5 of Fig. 1.

45 Except as hereinafter stated, the device may be made of any suitable materials, and the relative sizes and proportions of the same may be varied to a considerable extent without departing from the spirit of the invention hereinafter more fully set forth and 50 specifically claimed.

55 The seat portion 10 of the device comprises a series of parallel bars 11, 12 and 13, each of which is shown as comprising a pair of telescoping members so as to accommodate the length of the seat to the width of

the window. The bars 11 and 13 may preferably be of heavier and more substantial material than the intermediate bars 12. All of the bars at one end are connected by an end bar 14 and at the other end by a similar 60 bar 15. Each of the bars is connected permanently and rigidly at the ends of the respective sections of the bars 12 and adjacent the ends of the bars 11 and 13. Adjacent the front bar 13 the first bar 12^a is bent at its 65 ends 12^b and secured to the next bar 12, making provision for slides 16 on the inner ends of the end bars 14 and 15, said slides being provided with toothed shanks 17 adapted to engage over the upper surface of the windowsill S. Each shank on its end is provided with a finger 18 having a knuckle joint 19 to limit its movement substantially to a right angle. The finger, however, is adapted to fold up against the bottom of the shank 70 as shown in Fig. 2, where it will be held by means of the dog 20 pivoted at 21 and under the force of a leaf spring 22. When in adjusted or operative position the dogs 20 co-operate with the teeth 23 of the shanks so as 75 to limit the relative longitudinal movement of the slides and shanks along the end rods 14 and 15. In other words, the shanks and the fingers 18 hinged thereto will be adjusted in accordance with the width of the window- 80 sill and there locked by means of the spring pressed dogs 20. The ends of the rod 13 have plungers or bolts 24 adapted to be projected beyond the said ends so as to interlock with the inner wall of the building 85 at the window casings. Each of the bolts 24 is projected and controlled in its position by means of a thumb piece 25 operating along in a bayonet slot 26. When the bolts 24 are projected the entire construction is prevent- 90 ed from being precipitated from the window. A back rail 27 likewise telescopic in its nature is journaled in the hubs 28 of arms 29 connected to or journaled upon the outer rail 11. Said back rail 27, when thrown up- 95 wardly and rearwardly as shown in Fig. 1, so as to stand substantially perpendicularly to the seat 10, will be maintained in position by a pair of jointed braces 30. Each of said braces is hinged at 31 adjacent one end of 100 the bar 27 and at its other end at 32 to a link 33 pivoted at 34 in one of the cross bars 35. These cross bars lie parallel and closely adjacent the aforesaid end bars 14 and 15 105 and are connected at their ends to the ends 110

of the bars 11 and 13. The braces 30 are so arranged that their joints 34 break inwardly toward each other when the device is folded.

A pair of standards 37 are pivoted at 38 to the cross bars 35 substantially at their middle points and extend above and below the same, as shown best in Fig. 1. Each of these standards is composed of two parallel members connected at their upper ends by means 10 of a loop or clevise 39 which permits said standard to fold down closely upon its cross bar 35, as shown in Fig. 2. Braces 40 are pivoted intermediate their ends to the lower ends of the standards 37, each brace lying 15 between the lower ends of the standards and connected thereto by means of a pivot pin 41 and having at its outer end a ball 42 slideable along a slot 43 and within the cross bar 35. The lower end of each brace 40 is adapted 20 to rest against the outer wall of the building. The standards are maintained in stable position when the device is in operation by means of pawls 44 pivoted at 45 to the cross bars 35 between the pivots 34 and 25 38. Each of the pawls is adapted to interlock with teeth 37' formed on the front face of each standard 37, and since the standard is composed of two members, each pawl likewise has a pair of engaging fingers 44'. It 30 is to be noted also that the braces 30 extend between the several pairs of members constituting the braces 37 whereby when the standards are upright and are so held by the pawls 44, the braces 30 cannot break at their 35 joints 36, and hence the back rail 37 is maintained in its upright position.

To remove the device from a window the operator swings the pawls 44 toward the window on their pivots 45, and then the standards 37 may be likewise swung until the tops of the clevises 39 engage the cross bars 35. During this movement of the standards the ball ends of the braces 40 move outwardly toward the arms 29 of the back. The 40 45 braces 30 may then be broken, allowing the back to swing forwardly, and the braces will then occupy the position shown in Fig. 3. The platform may then be lifted in

through the window and passed through another window to be cleaned. The shanks 50 and fingers 18, and also the bolts 24, may remain in a definite position throughout the cleaning of any number of windows of the same character. If, however, the device is to be folded away for future use, the folding 55 may be effected by retracting the bolts 24 and bending the fingers up, as shown in Fig. 2.

Having thus described my invention, I claim as new and desire to secure by Letters 60 Patent:—

1. In a window cleaning platform, the combination of a seat portion including a pair of cross bars at its ends, a back hinged to the rear edge of the platform and movable through an angle of 90 degrees, hinged braces limiting the said movement, said braces being hinged at their ends to the back and to said cross bars, and means to support the platform in substantially horizontal position on the outside of a window, said supporting means including a pair of standards normally preventing movement of the braces on their hinges and acting therefore to prevent movement of the back aforesaid, substantially as set forth.

2. In a window cleaning platform, the combination of a seat portion, a back rail, a pair of hinged braces connected to said rail and limiting its outward movement, said braces being pivotally connected at both of their ends to the back rail and to said seat portion and having their middle portions breakable toward each other in folding, and devices connected to the seat portion serving to support the same against the outer wall, said supporting devices in normal position preventing the breaking of said back rail jointed braces.

In testimony whereof I have signed my name to this specification in the presence of two subscribing witnesses.

HENRY BOTTJER.
